UNITED STATES PATENT OFFICE.

SEBASTIAN G. BRINKMAN, OF FORDS, NEW JERSEY.

FLOAT-VALVE MECHANISM FOR CARBURETERS.

1,172,578.

Specification of Letters Patent. Patented Feb. 22, 1916.

Application filed November 5, 1914. Serial No. 870,364.

To all whom it may concern:

Be it known that I, SEBASTIAN G. BRINKMAN, a citizen of the United States, and a resident of Fords, in the county of Middlesex and State of New Jersey, have invented certain new and useful Improvements in Float-Valve Mechanism for Carbureters, of which the following is a specification.

This invention relates to a float valve mechanism for carbureters, by which the inflow of the gasolene into the liquid fuel chamber is regulated.

The invention comprises more particularly novel and efficient means for maintaining the float always at right angles to its axis of movement so that any jamming of the valve and its operating parts is effectively prevented.

In the accompanying drawing: Figure 1 is a vertical central section of a float valve mechanism embodying my invention, showing the same applied to a carbureter; Fig. 2 a cross section on line 2—2 Fig. 1, and Fig. 3 a perspective view of the valve-actuating fork.

Around the shell 1 of a carbureter of suitable construction, is fitted an annular liquid fuel chamber 2, shown to consist of a head 3, a base 4, and a round transparent side 5. From base 4 there extends upwardly, a pair of posts or bearings 6, in which is journaled by pin 7, a fork A, which is more fully shown in Fig. 3. This fork is composed of a web 8, a pair of shanks 9 extending inwardly therefrom, and a pair of parallel lugs 10, extending outwardly therefrom. Web 8 is located between bearings 6, and is apertured as at 11, for the accommodation of pin 7. Shanks 9, diverge from each other and are movably secured to the lower side of an annular float 12 which is vertically slid able along that portion of carbureter shell 1, which extends axially through chamber 2. The movable connection between shanks 9 and float 12 is effected by a pair of staples or keepers 13 which are driven into the float and loosely straddle the shanks, so that in this way, a rising or falling movement of the float will cause the fork A to turn slightly in its bearings 6. The body of web 8 is partly cut out, and the cut out portions are bent backward at right angles to the web, to form the parallel lugs 10. These lugs engage the neck 14 of a vertically movable tappet valve 15, which is adapted to be seated on a nipple 16, through which the

liquid fuel is admitted to chamber 2. It will be seen that as float 12 falls, lugs 10, will lift the valve, while when the float rises, the lugs will close the valve, so that in this way the supply of the fuel is regulated by the position of the float, which is in turn controlled by the quantity of gasolene supplied by chamber 2 to the carbureter.

In order to steady the movement of the valve operating means described, there is installed a second fork B, which is mounted with its axis at right angles to that of fork A and consequently crosses the latter. This second fork is composed of a web 17 and a pair of diverging shanks 18 extending inwardly therefrom. Web 17 is by pin 19 pivoted to a pair of posts 20, extending upwardly from base 4, and located at right angles to posts 6. Shanks 18, are slidably secured to the lower face of float 12 by staples or keepers 21, which loosely encompass the shanks and are arranged intermediate staples 13. It will be seen that by the construction described, each of the forks engages the float at diametrically opposite points, while the points engaged by one of the forks are located midway between the points engaged by the other fork. As the comparatively long bearing pins 7 and 19 respectively of the forks A and B preclude any lateral dipping of said forks, it is evident that owing to the peculiar overlapping thereof the annular float is bound to always occupy a position that extends in parallelism with the top and bottom of chamber 2. In other words, the float 12 although absolutely free to follow the general fall and rise of the liquid level, within chamber 2, cannot participate in any deflections of the liquid surface out of the horizontal, due to shocks, sudden changes in speed, varying inclinations of the car, etc., but said float will invariably occupy a position extending at right angles to the axis of chamber 2, so that any undesirable vibratory movements and a jamming between the float, its guiding means and the fuel inlet valve is effectively prevented.

I claim:

1. A float valve mechanism for carbureters comprising a fuel chamber, an inclosed float, a pair of independent forks each of which engages the float, and a valve operatively connected to one of the forks.
2. A float valve mechanism for carbureters comprising a fuel chamber, an inclosed

110

float, a pair of independent forks set at right angles to each other, one of said forks engaging the float at points located midway between the points of engagement of the other fork with the float, and a valve operatively connected to one of said forks.

3. A float valve mechanism for carbureters, comprising a fuel chamber, a pair of pivoted forks, set at right angles to each other and oscillable on horizontal axes only, a boat directly engaged by each of the forks at points located midway between each other, lugs extending from one of said forks, and a valve operatively engaged by said lugs.

4. A float valve mechanism for carbureters, comprising a fuel chamber, an inclosed float, a plurality of members that are oscil-

lable on a horizontal axis only and are each adapted to directly engage the float at different points, and a valve operatively connected to the float.

5. A float valve mechanism for carbureters, comprising a fuel chamber, an inclosed float, a plurality of fixed bearings arranged sidewise of each other, a plurality of members pivoted to said bearings and oscillable on a horizontal axis only, means for movably connecting said members to the float, a valve, and means on one of said members for actuating the valve.

SEBASTIAN G. BRINKMAN.
